UNITED STATES PATENT OFFICE.

PETER HAMEL, OF WAUKEGAN, ILLINOIS.

DUMPING CAR.

Application filed November 28, 1924. Serial No. 752,612.

This invention relates to improvements in railroad dumping cars of the type in which the body of the car is dumped or tilted with respect to the sills and supporting truck, to discharge the contents of the car, and has for one of its objects the provision of improved mechanism for tilting the car and which mechanism is operated by fluid pressure, the fluid pressure being under the control of valves located in a convenient position or in the engine cab.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which—

Figure 1 is a view in side elevation, partly broken away and partly in section of an improved car of this character constructed in accordance with the principles of this invention.

Figure 2 is a sectional view as taken on line 2—2, Figure 1.

Figure 3 is a diagrammatic view of the locking mechanism and the operating mechanism therefor.

Referring more particularly to the drawings the dumping car to which this invention is adapted to be applied, is of the type consisting of a body 10 pivotally supported on a central longitudinal axis spaced below the floor of the body and the fulcrum is preferably formed by means of standards or uprights 11 supported by the sills 12 above the trucks 13.

Any number of these standards may be employed and may be of any desired height according to the height that the body is disposed above the sills. The body is pivotally connected with the standards 11 by means of pivot pins 14 which pass through suitable ears 15 depending from the car bottom and also through the uprights 11.

Supported by the sills 12 in any desired or suitable manner preferably beneath the sills is a supporting member 16, which projects laterally beyond the sills and terminates adjacent the opposite sides of the car body 10. Telescoping cylinders 17 and 18 are provided for tilting the car body about its pivot 14. The cylinder 17 is pivotally supported as at 19 upon the member 16 and

within the cylinder 17 is a piston 20, having connected therewith a piston rod 21, the latter extending through the top of the cylinder 18 and is pivotally connected as at 22 with a bracket 23 secured to the car body 10.

One of these cylinder devices is arranged adjacent each side of the car and on opposite sides of the sills 12. Any number of cylinders may be provided, but in the form of the invention shown herein, four cylinders are employed, two of the cylinders being disposed adjacent each of the ends of the car body.

When fluid is admitted into the cylinders 17 beneath the piston 20 this piston will be first moved in the cylinder 18, thereby rocking the car body about its pivot 14. As soon as the piston 20 reaches the limit of its outward movement the fluid in the cylinder 17 will then move the cylinder 18 outwardly from the cylinder 17, the car body being tilted according to the particular cylinder devices which are rendered active.

By the arrangement of the telescoping cylinders, together with the piston 20, it will be manifest that the dumping mechanism may be arranged within the minimum and a very compact space, and at the same time the telescoping cylinders will permit of any desired degree of movement of the car body about its pivot. The pivotal connection 19 of the cylinder 17 with the supporting member 16 permits the cylinders and piston rod to rock to correspond to the dumping movement of the car body, so as not to interfere with the dumping operation and the righting movement of the car body.

Fluid may be admitted into the cylinder 17 from any suitable source through a supply pipe 24, to which supply pipe any number of flexible pipes 25 may be connected to lead to the dumping mechanisms on one side of the car body. The dumping mechanisms on the other side of the car body may be supplied with fluid through a similar pipe and similar connections.

The flow of fluid through the pipes 24 may be controlled by any suitable valve mechanism (not shown) and located in any convenient position on the car or in the engine cab.

The dumping mechanisms are so controlled that when fluid is admitted to the cylinders on one side of the car it will be exhausted from the cylinders on the opposite side of the car so as to allow the car body to

be swung in one direction about its pivot.

When it is desired to return the car body the fluid is exhausted from the active cylinders and admitted into the inactive cylinders.

Any suitable means may be provided for locking the car body against accidental movement about its pivot and for that purpose may be provided any number of 10 hangers or sector elements, which are secured to the car body and which preferably pass beneath the sills 12. The element 26 is preferably provided adjacent the front end of the body and is provided with lugs 27 projecting laterally therefrom and adapted to co-operate with suitable locking pins each of which is adapted to be normally projected by means of a spring 29 so that when the lugs 27 are moved into the proper position 15 with respect to the locking pins, the latter will co-operate therewith to hold the car against rocking movement.

A suitable lever 30 is pivotally mounted intermediate its ends as at 31 and is connected 20 at one extremity as at 32 with a pin 28 on one side of the car. To the other end of the lever 30 is connected a bar or rod 33 and this bar or rod is connected by a pin and slot connection 34-34^a with a cross bar or 25 lever 35, the latter being pivotally mounted intermediate its ends as at 36.

The bar or lever 35 is connected as at 37 with a piston rod 38 of a piston 39 that moves in a cylinder 40. The rear pin 41 on 30 the same side of the car as the pin 28, and which co-operates with the rear hanger or sector member 42, is pivotally connected as at 43 with a lever 44, the latter being pivotally mounted intermediate its ends as at 45. 35 Connected with the other end of the bar or lever 44 as at 46 is a rod 47 which is also connected with the lever 35 and is provided with a slot 47^a for the reception of the pin 34. On the opposite side of the car the locking pin 48 at the front of the car is pivotally connected as at 49 with a bar or lever 50, the latter being pivotally mounted intermediate its ends as at 51, and a bar or rod 52 is pivotally connected with the lever 50 at one end 40 as at 53 and at its other end by a pin and slot connection 54-54^a with the lever 35. The pin 55 at the rear of the car and on the same side as the pin 48 is pivotally connected as at 56 with a lever 57 pivotally mounted intermediate its ends as at 58, and pivotally connected as at 59 with the lever 57 is one end of a bar or rod 60, which latter is also pivotally connected with the lever 35 through the medium of a slot 60^a which receives the 45 pin 54.

With this construction it will be noted that when the lever 35 is rocked about its pivot 36, one of the locking pins at the front of the body on one side thereof and one of the locking pins at the rear of the body on

the other side thereof will be operated or rendered active while the other pins will be rendered inactive, and vice versa.

The pins 41 are adapted to respectively co-operate with lugs 61 and 62 on the rear sector or hanger member 42.

The piston 39 is adapted to be moved in one direction in the cylinder 40 by means of fluid supplied to the cylinder through a suitable pipe 63 leading from a suitable source 75 of supply. Fluid may also be supplied to the other end of the cylinder 40 to move the piston 39 in the opposite direction, through the medium of a pipe 64 leading from a suitable source of supply. The flow of fluid in 80 the pipes 63 and 64 is controlled by means of suitable valves located in a convenient position on the car or in the engine cab, and the valve mechanism is such that when one of the pipes 63-64 is opened to admit the fluid to flow into the cylinder 40 on one side of the piston the fluid in the cylinder on the opposite side of the piston will be forced 85 therefrom through the respective pipes 64- 90 63.

By the operation of the piston 39 the locking pins 28 and 55 will be retracted to permit the car body to be swung about its pivot in one direction, and the movement of the piston 39 in another direction in the cylinder 95 will retract the pins 48 and 41 and permit the pins 28 and 55 to assume their normal positions, to permit the car body to be swung in the opposite direction about its pivot.

While the preferred form of the invention 100 has been herein shown and described, it is to be understood that various changes may be made in the details of construction and in the combination and arrangement of the several parts, within the scope of the claims, 105 without departing from the spirit of this invention.

What is claimed as new is:—

1. A dumping car body, running gear, means pivotally supporting the body upon the running gear, hangers connected with the body and depending therebelow, said hangers being spaced longitudinally of the body, a pair of locking bolts co-operating with each of the said hangers for maintaining the car body in a horizontal position, means operatively connecting the bolts, said means embodying formations whereby locking bolts at the opposite ends of the car body and on opposite sides of the body will be simultaneously actuated, and means for controlling at will the actuation of said locking bolts.

2. A dumping car body, running gear, means pivotally supporting the body upon the running gear, fluid actuated means for tilting the body, hangers connected with the body and depending therebelow, said hangers being spaced longitudinally of the body, a pair of locking bolts co-operating with each of the said hangers for maintaining the car 130

body in a horizontal position, means operatively connecting the bolts, said means embodying formations whereby locking bolts at the opposite ends of the car body and on 5 opposite sides of the car body will be simultaneously actuated, and fluid actuated means for actuating said locking bolts.

3. A dumping car including a body, running gear, means pivotally supporting the 10 body upon the running gear, means for tilting the body, means for locking the body to maintain the same in a horizontal position and against tilting movement, the last said means embodying a plurality of locking devices 15 at each end of the body, the locking devices at each end being disposed on opposite sides of the body, and means connecting each of the locking devices at one end of the body with one of the locking devices at the other 20 end and on opposite side of the body for simultaneous operation, and means for controlling said locking devices whereby when one of the 25 connected pair of locking devices is rendered active the other connected pair will be rendered inactive.

4. A dumping car including a body, running gear, means pivotally supporting the body upon the running gear, means for tilting the body, means for locking the body to maintain the same in a horizontal position 30 and against tilting movement, the said means embodying a plurality of locking devices at each end of the body, the locking devices at each end being disposed on opposite sides of the body, means connecting each of the locking devices at one end of the body with one of the locking devices at the other end and on opposite sides of the body for simultaneous operation, means for controlling said locking devices whereby when one of the 40 connected pair of locking devices is rendered active the other pair will be rendered inactive, the last recited means including a single operating lever, and fluid controlled means for actuating the said lever. 45

In testimony whereof I have signed my name to this specification, on this 22nd day of November, A. D. 1924.

PETER HAMEL.
